CLAIM

The ornamental design for a portable tower with electrical outlets, as shown and described.

DESCRIPTION

FIG. 1 is a front perspective view of a first embodiment of the portable tower with electrical outlets showing our new design;

FIG. 2 is a front elevation thereof;

FIG. 3 is a rear elevation thereof;

FIG. 4 is a top plan view thereof;

FIG. 5 is a right side elevation thereof;

FIG. 6 is a left side elevation thereof;

FIG. 7 is a front perspective view of a second embodiment of the portable tower with electrical outlets showing our new design;

FIG. 8 is a front elevation thereof;

FIG. 9 is a rear elevation thereof;

FIG. 10 is a top plan view thereof;

FIG. 11 is a right side elevation thereof; and,

FIG. 12 is a left side elevation thereof.

In the drawings, the broken lines are for the purpose of illustrating environment only and form no part of the claimed design.
